UNITED STATES PATENT OFFICE.

ELMER A. SPERRY, OF BROOKLYN, NEW YORK, ASSIGNOR TO SPERRY DEVELOPMENT COMPANY, OF DOVER GREEN, DELAWARE, A CORPORATION OF DELAWARE.

MEANS FOR COOLING THE PISTONS OF HEAT ENGINES.

Application filed April 26, 1922. Serial No. 556,784.

This invention relates to the cooling of the pistons of heat engines, especially of pistons of internal combustion engines of the auto-ignition type, in which a very high mean 5 temperature is maintained. As is now well understood, the solution of this problem lies in abstracting heat from the head of the piston as rapidly as possible. For this purpose, it has been proposed to water cool the under 10 surface of the piston head, by circulating water through the interior of the piston from an external source. This method however involves the use of sliding parts, with its attendant complications. It has also been proposed to seal or confine within the piston a 15 liquid which may or may not completely fill the same. As explained in my prior applications for Letters Patent, Serial No. 486,181 for pistons for internal combustion engines, filed July 20th, 1921, and 529,314, pistons for 20 internal combustion engines, filed January 14th, 1922, such liquid acts to transfer speedily the heat from the piston head to the side walls of the piston from whence it is conducted by contact with the water cooled cylinder walls. This method of confining the liquid in a completely enclosed cavity in a 25 hollow piston also has serious drawbacks, first, since the liquid within the piston naturally becomes heated and will therefore 30 create an increasing vapor pressure within the piston, which may prove disastrous, and second, the liquid within the piston naturally churns up as the piston reciprocates rapidly 35 and as the pressure increases, becomes so mixed with the air in the cavity that the liquid becomes very "suds", so to speak, and does not act so effectively to abstract heat 40 from the piston as if unmixed with air.

The object of this invention is to overcome the defects of both types of cooling pistons above mentioned. Further objects will become apparent as the description proceeds.

Referring to the drawings in which what I 45 now consider the preferred forms of my invention are shown,

Fig. 1 is a vertical section through a hollow piston constructed according to my invention, together with the adjacent portions 50 of the cylinder.

Fig. 2 is an enlarged vertical section through a portion of said piston and the means employed for furnishing communication between the interior of the piston and the exterior thereof.

Fig. 3 is a section on line 3—3 of Fig. 2 looking in the direction of the arrows.

Fig. 4 is a detail showing the port in the piston affording connection with the outside open.

The type of piston I have chosen to illustrate the invention is a large low pressure piston 1, in which the under surface 2 thereof is employed as a compressor for precompressing the intake air for the engine. Both the upper surface 3 and the under surface 2 are therefore working surfaces which become more or less heated during the operation of the engine, although of course the upper surface is exposed to the greater heat. Said piston is as shown made hollow, so as to provide a space 4 within the piston adapted to contain a liquid 5, such as water, or preferably oil, which possesses a higher boiling point than water. The interior cooling surface of the piston exposed to the wash of the liquid may be increased by means of cooling fins 6. Preferably the liquid only partially fills the said space, so that it is alternately thrown against opposite ends of the piston as the piston reciprocates, thereby securing a very effective circulation of the liquid. Instead of sealing the liquid within said chamber however, I prefer to provide a port 7' or 8 a valve which leads outside of the piston, but which requires no sliding couplings. Said valve or port is shown as in the form of a tube 7 which extends within the piston to a point preferably above the normal level 8 of the liquid. Said tube also extends downwardly adjacent the bottom of the trunk 8 of the piston. A closure or valve 9 is provided for said port, said valve being preferably located within the piston. As shown, the valve is of the umbrella or petticoat type so that the spray and splash of the liquid will drain off the overhanging edge, and not enter the port 7' even when valve 9 is lifted. Said valve is provided with an elongated stem 10 which extends downwardly through said tube and is provided at its lower end with a collar or an abutment 11. Said stem is shown as guided within the tube adjacent its upper and lower end by guide blocks 12, 13 (see Figs. 2 and 3). Preferably I removably support the tube 7 on the piston as by mounting it within a larger tube 14. The latter is shown as extending through a clamp 15.

2
bolted to a projection 16 on the interior of the trunk 8 and also is threaded at 17 in the lower wall of the cavity in the piston. Said outer tube is made of sufficient diameter to permit both the inner tube 7 and the valve 9 thereon to pass through said tube 14. The inner tube and valve are normally held in place by means, such as a threaded collar 18, which may be secured to the inner tube and threaded on the interior of the outer tube. Said valve 9 is normally held on its seat by gravity or other yielding means such as a spring 19 held between the collars 11 and 18. Means are provided to open said valve whenever this may be done, without danger of permitting the liquid to escape from the interior of the piston. For this purpose, I provide means for opening the valve whenever the piston is near the end of its down stroke, at which time the liquid will obviously be collected in the bottom of the cavity due to the usual rapid deceleration of the piston as it nears the end of its stroke. As shown, said means consists of an abutment 20 which is preferably adjustable as by being provided with a threaded stem 21, threaded in bracket 22 secured to the guide 23 of the engine. It will readily be seen that whenever the piston approaches the limit of its down stroke, the collar 11 will come in contact with abutment 20 and force the valve stem and valve 9 upwardly to open the valve. This will at once place the interior of the piston in communication with the atmosphere and relieve the piston from any excess air or vapor-pressure, without at the same time permitting any liquid to escape. It is of course obvious that the valve may be biased in the open position and made to close when the piston approaches the upper end of its stroke, if desired, this being merely a reversal of the operation.

The normal level of the liquid as shown is about on the level with the top of the outer tube 14. Said tube therefore may act as a valuable means for gauging the amount of liquid within the piston. Thus in filling the piston, it may be filled until it begins to overflow from the pipe. Also the pipe 14 may be used to assist in filling, by removing from said pipe the inner pipe 7 and the valve 9. A small rubber hose may then be inserted through the pipe 14 and the liquid forced therethrough until the liquid begins to overflow through the pipe. If at any time it is desired to find out whether the liquid within the piston has been reduced below its proper level, it is simply necessary to take out the tube 7 with the attached parts, and to move the piston slightly, thereby setting up small waves in the liquid. If no liquid then splashes over into the tube 14, a fairly good indication will be obtained that the liquid level is materially below that of the

top of the tube and that additional liquid is required.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is,

1. A hollow piston for internal combustion engines adapted to contain a substantially unchanging body of liquid for cooling the same, a port leading from within said piston to the outside of the same, and means for intermittently closing said port.

2. A hollow piston for internal combustion engines adapted to contain a substantially unchanging body of liquid for cooling the same, a port leading from within said piston to the outside thereof, a valve normally closing said port and means for opening said valve whenever this may be done without permitting the liquid to escape.

3. A hollow piston for internal combustion engines adapted to be partially filled with a substantially unchanging body of liquid for cooling the same, a port leading from within said piston to the outside thereof, a valve normally closing said port and means for opening said valve when the liquid is at the opposite end of the piston from said port.

4. A hollow piston for vertical reciprocating engines adapted to be partially filled with a substantially unchanging body of liquid for cooling the same, a port in said piston above the normal level of the liquid and means for closing said port when the liquid is thrown upwardly above its normal level.

5. A hollow piston for internal combustion engines adapted to be partially filled with a liquid, a port in said piston, a valve within said piston normally closing said port, a stem for said valve leading without said piston, yielding means for holding the valve normally closed, and an abutment against which said stem strikes on reciprocation of the piston.

6. A piston for vertical heat engines having a cavity, and means for filling said cavity with liquid to a predetermined level comprising a tube carried by said piston and extending from without the piston up through

said cavity to about said predetermined liquid level and means for closing said tube.

7. A piston for vertical heat engines having a cavity adapted to contain a liquid, a tube extending within said cavity above the normal liquid level, a valve for closing the upper end of the tube, a stem for said valve extending through the tube below the cavity, and an abutment against which said stem is adapted to strike on reciprocation of said piston.

8. A piston for vertical heat engines having a cavity adapted to contain a liquid, a tube extending within said cavity above the normal liquid level, a valve for closing the upper end of the tube, a stem for said valve extending through the tube below the cavity, a second tube secured to said piston, enclosing said first tube and extending within the piston to about the normal liquid level and an abutment against which said stem is adapted to strike on reciprocation of said piston.

9. A hollow piston for vertical reciprocating engines adapted to be partially filled with a liquid for cooling the same, a port in said piston above the normal level of the liquid and an umbrella valve for closing said port when the liquid is thrown upwardly

30 above its normal level.

10. A hollow piston for internal combustion engines adapted to be partially filled with a substantially unchanging body of liquid for cooling the same, means connecting the space above the liquid within said piston with the outside of said piston, means normally closing said first named means, and means for periodically operating said last named means to open said first named means and reduce the vapor pressure in said piston. 35 40

11. A hollow piston for internal combustion engines adapted to be partially filled with a substantially unchanging body of liquid for cooling the same, and means for periodically permitting the reduction of vapor pressure in said piston without permitting the escape of liquid therefrom. 45

12. A hollow piston for internal combustion engines adapted to be partially filled with a substantially unchanging body of liquid for cooling the same, a port connecting the space above the liquid within said piston with the outside of said piston, a valve normally closing said port and means for periodically opening said valve to permit reduction of the vapor pressure within said piston. 50 55

In testimony whereof I have affixed my signature.

ELMER A. SPERRY.
